UNITED STATES PATENT OFFICE.

JEFFERSON PATTEN, OF BROOKLYN, NEW YORK, ASSIGNOR OF ONE HUNDRED AND THIRTY-FOUR TWO-HUNDREDTHS TO IVERS A. GARD, OF BERGEN POINT, CHARLES KENNEDY HAMILTON, JR., OF SUMMIT, AND CHARLES H. MUNDY, OF METUCHEN, NEW JERSEY.

HYDROCARBON-FURNACE.

SPECIFICATION forming part of Letters Patent No. 392,285, dated November 6, 1888.

Application filed June 23, 1887. Serial No. 242,224. (No model.)

To all whom it may concern:

Be it known that I, JEFFERSON PATTEN, of Brooklyn, (Green Point,) county of Kings, and State of New York, have invented a certain new and useful Improvement on Hydrocarbon-Furnaces, of which the following is a specification.

I will describe my improvement in detail and then point out the novel features in the claims.

10 In the accompanying drawings, Figure 1 is a plan view, partly in section, of a hydrocarbon-furnace embodying my improvement, taken on the plane of the dotted line xx , Fig. 2. Fig. 2 is a vertical section of the same and 15 showing parts of the steam-boiler broken away to save space, said figure being taken on the plane of the dotted line yy , Fig. 1. Fig. 3 is a front view of parts of the same.

Similar letters of reference designate corresponding parts in all the figures.

A designates a combustion-chamber. It may be made of metal, preferably of iron. Its upwardly-extending end a is shown as bell-shaped and is open at the top. Below the 25 bell-shaped portion the combustion-chamber extends in an approximately horizontal direction toward the front of the furnace, and is, as shown, cylindrical, or approximately so, upon its interior. This cylindrical portion has formed in it and extending about it upon its 30 exterior an annular air-passage, B. This air-passage communicates with the external atmosphere. I have shown openings (marked b) for this purpose which open upon the outside 35 of the furnace. The annular air-passage communicates, as here shown, at the lower side of the combustion-chamber with a vertically-arranged air-pipe, C, which is also centrally arranged in the upwardly-extending portion a .

40 The combustion-chamber is supported at its rear end, as shown, upon a leg, c' , bolted or otherwise secured to any suitable support, and at its front side upon a plate, c^2 , also supported on a suitable support.

45 D designates the front of the furnace. It is supported, as shown, on the plate c^3 . Extending inwardly from this plate is a ring, c^4 , which ring surrounds a portion of the combustion-

chamber, which includes the annular air-passage. Another ring, c^5 , extends inwardly from 50 the plate D within the combustion-chamber. Between the rings c^4 c^5 and the combustion-chamber any suitable packing may be interposed to form a rust-joint.

E E' designate a combined inlet for hydrocarbon oil and a gas-retort. As shown, this inlet and gas-retort are made of a single piece of pipe. The oil-pipe extends, as shown, to and around the air-flue C, during which it is subjected to the action of heat in the combustion-chamber in a manner to be presently described, whereby the oil becomes vaporized and returns through the vaporizing-retort E', as shown, to the exterior of the furnace. 55

Secured to the outwardly-extending end of 60 the vaporizing-retort is a U-shaped pipe, E''. This pipe is shown as gradually lessening in diameter from its point of connection with the retort E' to its point of connection with a short pipe, E', which in effect constitutes a continuation of the pipe E''. The pipe E' returns into the furnace through a suitable opening in the plate D. By reducing the diameter of the pipe 65 e^3 in the manner shown the vaporized oil or gaseous product is caused to flow through the pipe E' under considerable pressure and therefore with increased force. 70

I have shown the aperture in the plate D, through which the pipe E' extends, as somewhat larger in diameter than the pipe E', 80 whereby an annular passage is formed around the pipe E', through which atmospheric air will be admitted to the interior of the combustion-chamber, and will mix with the vapor issuing from the pipe E', in order to facilitate 85 combustion.

G designates a pipe, preferably of slight diameter, which communicates near its outer end with a supply-pipe for oil, E''. This pipe extends into the interior of the combustion-chamber through a suitable aperture in the plate D, and is employed for the purpose of supplying a small stream of oil to be ignited beneath the vaporizing-retort E' and oil-pipe E, in order to begin the operation of the furnace. 90 This stream of oil, when ignited, causes 95

the oil in the oil-pipe and the vaporizing-retort to be heated and the oil in the oil-pipe will become vaporized, whereupon the vapor will commence to flow through the pipe E' and into the interior of the combustion-chamber. It will then be ignited by the flame ascending from the pipe G, and the operation of the furnace is then established.

I have shown a cock, e, in the pipe G, whereby oil may be prevented from flowing through said pipe when the furnace is in operation.

In starting the operation of the furnace, oil is supplied to the oil-inlet pipe E from the pipe E', receiving a supply of oil from any suitable receptacle, maintained preferably in an elevated position, so that oil will flow into the oil-pipe by means of gravity.

I desire to mix steam with the oil flowing through the oil-pipe E, and for this purpose, after the operation of the furnace has commenced, as described, I shut off the flow of oil from the oil-supply pipe E' by means of the cock h. A steam-injector, J, (illustrated more clearly in Fig. 2,) and which may be of the usual or any ordinary construction, is employed to cause a flow of oil from a pipe, J', communicating with an oil-tank (not shown) by creating a partial vacuum in the pipe J', in a well-known manner. The ignited vapor passes upwardly into the bell-shaped upper portion of the combustion-chamber, where it becomes mixed with jets of air flowing through horizontally-arranged apertures f in the upper end of the air-flue C. This mingling of the air and the gaseous flame causes an intense heat and very perfect combustion.

I have shown my improved furnace as applied to a vertically-arranged steam-boiler, H, which may be of the usual or any ordinary construction; but the same may be applied to the heating of any other apparatus, if desirable.

It may be seen that this furnace is very simple in construction, cheap, and durable, and that it has no parts which are liable to get out of order, while it may readily be taken apart to repair or replace the oil-pipe and vapor-retort, if desirable.

What I claim as my invention, and desire to secure by Letters Patent, is—

1. In a hydrocarbon-furnace, the combination, with a combustion-chamber having a horizontally-extending portion, and an upwardly-extending portion having an open upper end, of an air-pipe extending vertically and centrally through the upwardly-extending portion of said combustion chamber, and provided near its upper end with horizontally-extending apertures, an air-passage with which said air-pipe communicates, and an oil-pipe and vaporizing-pipe extending into said combustion-chamber and subjected to the influence of the products of combustion, substantially as specified.

2. In a hydrocarbon-furnace, the combination, with a horizontal combustion-chamber having a vertically-arranged portion open at its upper end, of an air-pipe arranged vertically and centrally in said vertically-extending portion and provided with horizontally-extending apertures in its upper end, an oil-pipe extending from the exterior of said combustion-chamber into the same, and a vaporizing-retort communicating with said oil-pipe and extending to the exterior of the combustion-chamber, the vaporizing-retort being connected at its outer end with a pipe of gradually-lessening diameter returning to the interior of the combustion-chamber, substantially as specified.

3. In a hydrocarbon-furnace, the combination, with a horizontal combustion-chamber provided with an upwardly-extending portion having an open upper end of an air-pipe arranged vertically and centrally in said upwardly-extending portion and provided with horizontally-extending apertures near its upper end, of an annular air-passage formed in the wall of said horizontal combustion-chamber and communicating with said vertically-extending air-pipe, said annular air-passage having openings communicating with the external atmosphere, and an oil pipe and a gas-retort extending into the combustion-chamber, substantially as specified.
